AIR OR OIL OPERATED CYLINDER CLAMP

Leland F. Blatt, Grosse Pointe Woods, and
Arthur Sherman, Detroit, Mich.

Application January 26, 1955, Serial No. 34,230

Term of patent 14 years

(Cl. D55—1)

Fig. 1 is a perspective view of an air or oil operated cylinder clamp showing our new design.

Fig. 2 is a side elevational view thereof.

Fig. 3 is a plan view thereof.

Fig. 4 is an end elevational view thereof.

Figs. 2, 3 and 4, for the purpose of illustration, show the release position of the present design, whereas, Fig. 1 illustrates the design in clamping position.

We claim:

The ornamental design for an air or oil operated cylinder clamp, substantially as shown.
